CLAIM

We claim the ornamental design for an electric screwdriver set, as shown and described.

DESCRIPTION

FIG. 1 is a front perspective view of an electric screwdriver showing our new design in accordance to a first embodiment;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and

FIG. 8 is a bottom plan view thereof.

FIG. 9 is a front perspective view of an electric screwdriver showing our new design in accordance to a second embodiment;

FIG. 10 is a rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and

FIG. 16 is a bottom plan view thereof.

FIG. 17 is a front perspective view of an electric screwdriver showing our new design in accordance to a third embodiment;

FIG. 18 is a rear perspective view thereof;

FIG. 19 is a front elevation view thereof;

FIG. 20 is a rear elevation view thereof;

(Continued)

FIG. 21 is a left side elevation view thereof;
 FIG. 22 is a right side elevation view thereof;
 FIG. 23 is a top plan view thereof; and,
 FIG. 24 is a bottom plan view thereof.
 The broken lines depict portions of the electric screwdriver
 in which the design is embodied that form no part of the
 claimed design.
